UNITED STATES PATENT OFFICE.

HANS LARSEN, OF NEWELL, IOWA, ASSIGNOR OF ONE-HALF TO H. P. JENSEN,
OF SAME PLACE.

ANIMAL-RELEASING DEVICE.

SPECIFICATION forming part of Letters Patent No. 530,487, dated December 4, 1894.

Application filed April 12, 1894. Serial No. 507,280. (No model.)

To all whom it may concern:

Be it known that I, HANS LARSEN, a citizen of the United States, residing at Newell, in the county of Buena Vista and State of Iowa, 5 have invented a new and useful Animal-Releasing Device, of which the following is a specification.

My invention relates to improvements in those stanchions which are made in series 10 and capable of being released in unison and by a simple and quick movement, whereby the animals secured thereby will be freed simultaneously; and the principal object of the invention is to provide a device of this 15 class which may be released with greater ease and speed than ordinarily, and one which can be manufactured at a low cost.

A further object of the invention is to provide a device whereby the animals will be 20 allowed more ease when secured thereby, and one which will not make it hard for them to rise from a lying position.

In the accompanying drawings: Figure 1 represents a perspective view of a portion of 25 a cow stable, showing my improvements in use; Fig. 2, an enlarged side elevation of one section of the stanchion; Fig. 3, a longitudinal section taken through the upper beam or box of the device and showing how the chains 30 are attached thereto; Fig. 4, a detail perspective showing the construction of the locking pin for holding the chains.

The reference numeral 1 indicates the 35 framework of the stalls, which consists of vertical and parallel beams secured at their tops to the transverse beam 2, or to the top of the stable.

3 indicates the pin or bar box, which contains the devices for supporting the upper 40 ends of the chains, and which is secured to the vertical beams 1, by bolting or otherwise. The box 3 extends horizontally and co-operates with the foot-board 4, which extends similarly and is secured to the lower ends of the 45 beams 1 at a point directly adjacent to the floor.

5 and 6 indicate the chains for securing the animals in place, and these are essentially two in number, though I have shown three 50 sets in the drawings. The chain 5 is permanently secured to the beam or board 4, by

means of the eye 7, and extends up to the box 3, and is provided at its upper extremity with the link 8, which projects into the box and is removably secured therein, as will be 55 better described hereinafter. The chain 6 is provided with the eye 9, at its upper end, and this is secured to the hook 10 of the rear face of the box 3. This chain 6 is formed in two sections, and has the iron ring 11 interposed 60 between the contiguous ends of the sections and securely fastened thereto. Through this ring the chain 5 is passed, thus giving it a connection with chain 6, and allowing the ring 11 to slide freely on the chain 5. Secured to the lower end of the chain 6 is the ring 15, which receives the chain 5, and by this means the first chain is slidably connected to the latter. Thus it will be seen that the chain 5, when the device is in operative position, is connected securely to both the box 3 and board 4, and that the chain 6 is slidably connected to the first chain so as to form a loop thereon for the reception of the animal's neck, and that this loop is movable vertically on the chain 5 so as to be adjusted to the position which the animal occupies. 70

The chains 5 are secured to the box 3 by means of the longitudinally-extending bar 16, 80 which extends throughout the longitudinal extent of the box, and projects out beyond each end thereof. Located in the box 3 are the blocks 17, which fill the space not occupied by the bar 16, and serve to guide and 85 steady the same. These blocks 17 are secured in place by the bolts 18, which pass through them and the box 3, and which have their lower ends formed with hooks 10, by which chains 6 are secured in place. Secured 90 to the bar 16, at the left of each block 17, are the eyes 18^a, which are two for each block and which are longitudinally aligned on the bar. In each pair of these eyes the pins 19 are arranged so as to be longitudinally movable therein, and provided with the coiled springs 20, by which they are given a normal tendency toward their respective blocks. 95

21 indicates a series of eyes which are secured to the interior of the box, and one just 100 to the left of each block 17 and in the path of the pins 19. Through these eyes the pins

19 pass on their way to the blocks, and by these means they are steadied and rendered rigid. The coiled springs 20 bear, at their right-hand ends, against the studs 22, which 5 project upwardly from the pins 19, and through the longitudinally-elongated slots 23, on the top of the box 3. These slots 23 are one for each stud 22 and are formed to permit movement of the studs, and consequently 10 the bar 16.

Secured in the upper end of the studs 22 are the rings 24, which are adapted to serve as a convenient means for grasping the studs and by which they may be moved in their slots. 15

15 The chains 5 enter the box 3 by way of the openings 25, formed in the rear face of the box and between the eyes 18^a and 21 of each block 17, so that the links 8 will be in position to receive the pins 19, and thereby 20 secure the chains. Secured to each end of the box 3, and on opposite sides of the projecting ends of the bar 16, are the eyes 26, which 25 are two for each end of the box, and which are adapted for the reception of the pin 27.

25 The pin 27 is adapted to pass through the eyes 26 and through the openings 28 in the ends of the bar 16, and by that means hold the bar incapable of movement. Only one pin is provided, and this may be used at either 30 end, as convenient.

To use my invention the chains are connected to the box 3 and board 4 and to each other, as explained, and the lower end of chain 6 passed around the animal's neck and 35 secured to the chain 5 by means of the ring 15, thus securely fastening the animal and yet leaving him able to move his head up or down throughout the extent of the chain 5. It will be understood that the two chains 5 40 and 6, and the bar 16 with one pin 19, are the only essentialities of the invention, and that these may be multiplied *ad infinitum*, according to the number of animals to be secured. Thus I have shown three sets of 45 chains, with their appurtenances, and it will be obvious that this does not exhaust the number possible.

To release all the animals at once, all that

will be necessary is to withdraw the pin 27 and pull or push on the bar 16, according to 50 the end of the box at which the operator stands. This will move the pins 19 to the left and disengage the links 8 and pins 19, thus allowing the chains 5 to drop down through the ring 11, and thereby releasing 55 the animal secured by the chain. By this means all the animals in a stable may be simultaneously released, so as to allow their escape in case of fire, or to turn them out of the stable. If, however, it is desired to release only one animal, this may be done by moving the stud 22 of the pin 19 which holds the animal, thus causing the pin 19 to move independently and release the link 8 engaged by it. By this construction the animals may 60 be secured, since it would be quite inconvenient to secure them all at once.

In Fig. 1 I have shown the chains in three different positions; the chains on the extreme left being shown detached and in the positions they will occupy when the animal has been released; the next set, with the animal attached and showing him with his head raised; and the third, with the animal attached and with his head down.

Having described my invention, what I claim is—

The combination with upper and lower stanchion-bars, of a chain permanently secured at its lower end to the lower bar, a 80 spring-actuated bolt mounted upon the upper bar and adapted to engage a ring on the upper extremity of said chain, and a second chain permanently secured at its upper end to the upper bar and provided at its lower 85 end and at an intermediate point with rings which are slidably fitted upon the first chain, substantially as specified.

In testimony that I claim the foregoing as my own I have hereto affixed my signature in 90 the presence of two witnesses.

HANS LARSEN.
